UNITED STATES PATENT OFFICE.

HENRY W. O'DOWD, OF JERSEY CITY, NEW JERSEY, ASSIGNOR, BY MESNE ASSIGNMENTS, TO STANDARD GAS EQUIPMENT CORPORATION, OF BALTIMORE, MARYLAND, A CORPORATION OF MARYLAND.

THERMOSTATIC FLUID-CONTROLLING DEVICE.

Application filed September 6, 1924. Serial No. 736,297.

This invention relates to thermostatically operated heat regulating or controlling devices, and has reference more particularly to devices of this kind suitable for use in connection with ovens of gas stoves.

The general objects of the invention are to provide a device which is of simple construction and involves a minimum of parts; which is highly sensitive in action and capable of responding promptly to slight changes in temperature; which is positive and uniform in operation; and which may be readily and conveniently adjusted to vary the degree of the controlled temperature. With these and other objects in view, the invention consists of the improved arrangement and construction of parts illustrated in the accompanying drawings and described in detail in the specification to follow.

20 In the accompanying drawings:

Fig. 1 is a perspective view of a portion of a gas stove having the invention applied thereto, parts of the oven being broken away to show the interior;

25 Fig. 2 is a horizontal sectional plan view taken fore and aft of the oven on a line slightly above the thermostatic unit;

Fig. 3 is a vertical longitudinal section on an enlarged scale through the valve casing and the adjusting means for the thermostatic device, the section being taken on the line 3—3 of Fig. 2;

30 Fig. 4 is a cross section through the same taken on the line 4—4 of Fig. 3;

35 Fig. 5 is a horizontal longitudinal section taken on the line 5—5 of Fig. 3;

Fig. 5^a is a sectional view of a modified form of the adjusting means for the thermostatic device;

40 Fig. 6 is a sectional elevation of another modified form of the same;

Fig. 7 is a similar view of the adjusting means adapted for a different kind of installation;

45 Fig. 8 is an elevation of a gas stove of a different type from that shown in Fig. 1 and showing the improved thermostatic device applied thereto, a portion of the oven being broken away;

50 Fig. 9 is a side elevation of the same, with parts in section, as viewed in the direction of the arrow in Fig. 8;

Fig. 10 is a sectional plan view taken on the line 10—10 of Fig. 9; and

Fig. 11 is a sectional elevation taken on the line 11—11 of Fig. 9.

Referring more particularly to Figs. 1 to 5, the gas stove therein illustrated is provided with an oven 1 and an overlying cooking top 2, the latter being heated by burners (not shown) supplied with gas from a supply pipe or manifold 3, and the former being heated by a main burner 4 (Fig. 2) also supplied with gas from the manifold 3 in the manner presently to be described.

A thermostatic fuel-controlling device is employed for automatically regulating the supply of gas to the oven burner and for maintaining the temperature of the oven at the desired point. This device comprises essentially a thermostatic couple 5 and a valve 6 operated thereby, the said couple being supported within the oven where it will be subject to the influence of the heat, and the valve being disposed in the gas passage leading to the oven burner so as to regulate the flow of gas under the control of the thermostat.

The thermostatic couple 5 may be of any suitable and appropriate form or construction, but in the preferred embodiment illustrated, it comprises an external tube 7 of a metal having a relatively high coefficient of expansion, such as copper, and an internal rod 8 of a material having a low coefficient of expansion, such as invar or stoic metal or the like. One end of the rod 8 is fixed to the tube 7 as at 9, Fig. 2, so that the movement of the tube due to its expansion or contraction will be transmitted positively through the rod to the valve 6, which latter is fixed to the other end of the rod and adjustable thereon, as will be more fully described hereinafter.

The forward end of the thermostatic tube 7 is preferably attached to the rear side of a valve casing 10 supported by the side wall of the oven, such attachment being conveniently effected by screwing the tube into a threaded hole in the casing. The valve casing is extended outwardly through the wall of the oven and is divided by a partition 11 into two chambers, a gas receiving chamber 12 connected to the supply pipe or manifold 3 through a branch pipe 13 equipped with a cut-off valve 14, and a gas supply chamber 15

connected to the oven burner 4 through a pipe 16 terminating in a nozzle discharging into the flared mouth of the burner mixing tube 4^a (Fig. 2). It may be noted at this point that 5 there is associated with the oven burner 4 a pilot burner 17 which is supplied continuously with gas (when the oven is in use) by means of a feed pipe 18 leading directly from the receiving chamber 12. The gas supplied 10 to the main heating burner 4, on the other hand, must pass from the receiving chamber 12 into the supply chamber 15 of the valve casing, and during such passage, it is subjected to the regulating action of the thermostatically operated valve 6 before referred 15 to, which controls the communication between the two chambers. As best shown in Figs. 3 and 5, the valve 6 is in the form of a sliding piston and is fitted in a gas-tight manner 20 within a valve cylinder 20 formed within the receiving chamber 12 and entirely surrounded by an annular passage 19. The valve cylinder 20 is formed with an annular slot-like port 21 which communicates with an annular groove-like port 22 formed in the piston valve 6, the degree of communication between the two ports being dependent on the 25 position of the valve as controlled by the thermostatic couple. The piston valve is further formed with a number of axial ports or 30 holes 23 leading from the annular port 22 into the supply chamber 15, see Fig. 3.

From the construction described, it will be seen that the gas entering the chamber 12 will 35 pass around the annular passage 19 through the annular port 21 into the annular port 22, and thence out through the ports 23 into the supply chamber 15, whence it will be conducted to the burner 4 by the pipe 16. When 40 the temperature of the oven is high and causes a corresponding expansion of the thermostatic tube 7, the latter pulls rearwardly on the rod 8 and moves the piston valve 6 to the rear, thereby shifting its annular port 22 45 rearwardly relative to the port 21 in the valve cylinder 20 and restricting the communication between the two in order to reduce the supply of gas to the oven burner 4. When, however, the tube 7 contracts, due to a lower 50 temperature in the oven, the rod 8 is pushed in the opposite direction, and the piston valve correspondingly shifted to open up the ports and increase the supply of gas to the oven burner.

55 The piston valve 6 is screwed onto the end of the thermostatic rod 8, so that by turning it in one direction or the other, it may be adjusted relatively to the thermostatic couple to vary the temperature of the oven according 60 to the articles of food being cooked. This adjustment of the valve is effected, in the present instance, by means of an adjusting wheel 24 (Figs. 4 and 5) attached to a tapered hub 25 seated in a corresponding opening in

the front wall of the valve casing, and held 65 gas-tight to its seat by a spring 26 bearing between the wall and a washer 27 fixed to a stem 28 extending inwardly from the hub. This stem 28 is flattened at its end, as at 29, and is slidably fitted in a corresponding slot 70 30 formed in an axial extension 31 of the piston valve 6, so that the latter may be set in any desired position without breaking its connection with the adjusting wheel 24.

In installations of the character shown in 75 Figs. 1 to 5, the adjusting wheel is located on the inside of the oven, and in order that it may be turned from the outside, there is provided a right-angularly disposed dial head 32 rotatably mounted, as by means of a screw stud 33, 80 upon a lug 34 formed on an extension 35 of the valve casing and projecting outwardly through the side wall of the oven. The dial head is provided on its inner face with gear teeth 36 which engage gear teeth 37 on the periphery of the adjusting wheel 24, the edge of which extends through a slot 38 in the wall of the oven. Graduations 39 are placed on the dial head and are adapted to be read in connection with a pointer 40 fixed to the valve 85 casing or the side wall of the oven by a screw 41.

By the method shown of mounting the dial head, it can be adjusted circumferentially or in the direction of the spacing of the graduations thereon, relatively to the adjusting wheel and the valve operated thereby, by first loosening the screw stud 33 sufficiently to disengage the teeth on the dial head from the teeth on the wheel and then shifting the head around to the desired position, and again screwing up the stud to maintain the parts in their adjusted position. The purpose of this adjustment is to enable the parts to be set in their proper relative positions during 100 assemblage, it being understood that the gas in one locality may have a different thermal value and be under a different pressure from that existing in another locality, and in such conditions, by adjusting the dial head as described, the graduations on the dial may be caused, when positioned opposite the pointer 40, to indicate the actual temperature required under any given condition.

105 The dial head is limited in its movement to a single rotation through 360° by means of a stop pin 55 carried by the dial head in position to engage a stop lug 56 projecting from the side wall of the oven, the movement of the valve between its two extremes being 110 effected by the motion of the dial within a complete rotation.

115 The valve casing is formed with an opening 57 through the wall thereof and leading to the annular passage 19, which opening is normally closed by a screw plug 58, the purpose 120 being to enable a gauge to be inserted into the valve casing from the outside and positioned 125

in the annular ports 21 and 22 in order to effect the proper initial setting of the valve in the manner just described.

The pointer is formed with an elongated slot 42, through which the screw 41 passes, so as to be adjustable relatively to the dial head in order to compensate for any variations between the actual temperature of the oven and the temperatures indicated by the 10 graduations on the dial head. To enable the pointer to be more accurately adjusted in making corrections, it is provided with graduations 43 reading in both directions from a zero point and which are spaced to 15 correspond with the intervals between the graduations on the dial, it being understood that in any given locality, the condition of the gas or the pressure may cause fluctuations in the actual temperature of the oven, notwithstanding the initial adjustment already referred to.

The advantages of the foregoing arrangement of the parts will now be clear. Due to its direct connection to the thermostatic 25 couple, the valve 6 is highly sensitive and positive in action and responds instantly to temperature changes, there being no springs, or other articulated parts between the valve and the thermostatic couple so characteristic 30 of other constructions. Furthermore, owing to the comparatively large area of the annular ports 21 and 22, the piston valve, although thus directly connected to the thermostatic couple, insures an adequate and uniform supply of gas to the oven burner under all conditions of use. These and other advantages 35 will be readily appreciated by those skilled in the art.

As shown in Fig. 5, gas is allowed to flow 40 from the receiving chamber 12 to the supply chamber 15 through a by-pass opening 44 which is controlled by a throttling screw 45, the purpose being to insure that the main heating burner 4 is supplied with a limited 45 amount of gas continuously and independently of that controlled by the thermostatic valve 6, and this in order to prevent the supply of gas from being cut off entirely from the burner by the action of the valve. As before noted, 50 the supply of gas to the pilot burner 17 is also continuous and independent, so that this burner when once lighted will light the main burner and keep it lighted at all times until the gas is turned off by the hand operated valve 14.

In Fig. 5^a, a modified form of the connection for transmitting the rotary motion of the indicating head 32 to the valve is shown. In this case, the axis of the dial is disposed at 60 right angles to the axis of the valve, similar to the arrangement shown in Fig. 5, but bevel gears are employed in this case instead of crown gears as in Fig. 5. The dial head is formed with a hub 59, the bore of which 65 receives the outer end of an axle 60 rotatably

mounted in a bearing 61 projecting outwardly from the valve casing, the said bore being formed with axial teeth 62 entering grooves 63 in the end of the axle, so as to form a detachable driving connection between the 70 wheel and axis, the wheel being detachably confined on the axle by a fastening screw 64 screwed in the axle and having its head engaging the outer face of the wheel. This construction admits of the adjustment of the dial 75 head relatively to the parts operated thereby, in the direction of the spacing of the graduations, as before described in connection with Fig. 5, and for the same purpose. At its rear end on the inside of the oven wall, the axle 80 has fixed to it a bevel gear 65 which engages a bevel wheel 66 fixed to the outer end of the hub 25, similar in form and arrangement to the corresponding hub shown in Fig. 5 for transmitting the rotary motion of the dial 85 head to the controlling valve.

In Fig. 6, there is shown a combined adjusting wheel and dial head 46, which is adapted for a type of installation where the adjustment of the valve on the thermostatic 90 rod may be effected directly by the dial head on the outside of the oven.

In Fig. 7, the construction is the same as that first described, except that the axis of the adjusting dial head 32 is disposed obliquely with relation to the axis of the adjusting wheel 24, instead of at right angles to the same, this oblique relation of the parts being suited to a further type of installation. 95

Figs. 8, 9, 10 and 11 illustrate the invention 100 as embodied in a "cabinet" type of gas range, wherein an oven 1^a is arranged above and to one side of a cooking top 2^a, which latter is heated by burners supplied with gas from a supply pipe or manifold 3^a. In applying the 105 invention to gas stoves of this type, the thermostatic valve mechanism is arranged as before in the upper part of the oven, and the adjustments of the piston valve are made by operating the dial head 32 on the outside of the oven as previously described. In this instance, the valve casing 10^a is disposed wholly within the oven and is connected to the manifold 3^a by a pipe 47 extending rearwardly 110 from the manifold, a short pipe 48 extending transversely from the pipe 47 into the bottom of the oven, and a pipe 49 extending upwardly within the oven from the pipe 48 and connecting at its upper end with the gas receiving chamber of the valve casing. A vertical pipe 50 leads downwardly from the gas supply chamber of the valve casing alongside pipe 49 and connects at its lower end with a short pipe 51 which extends outwardly through the oven and communicates with the rear end of a pipe 52 leading forwardly beneath pipe 47 and communicating at its forward end with a pipe 53 which connects with pipe or manifold 54 supplying gas to the oven 115 burner. As a result of the construction de- 120

130

scribed, the gas from the manifold 3*, before it reaches the oven burner, is caused to pass through the valve casing 15*, where its flow is thermostatically controlled in the manner 60 previously described.

Wherever in the specification and claims a 10 port is mentioned in describing the ports 21 and 22, it is intended that the expression include a slot-like continuous port, as shown, or 10 a port made up of a series of individual holes or openings related to each other so as to conjointly form in effect an elongated or extended port, and to include also a port otherwise specifically formed to function similar 15 to the port shown.

In the foregoing description and accompanying drawings, the invention has been set forth in the particular detailed forms which it is preferred to adopt, but it will be manifest 20 that the details may be variously changed and modified without departing from the spirit of the invention. It should be understood, therefore, that the invention is not limited to any particular form or construction 25 of the parts except in so far as such limitations are specified in the claims.

What I claim is as follows:—

1. In a thermostatic fuel controlling device for gas burners or the like, the combination 30 of a thermostatic couple subject to heat generated by the burner, a valve casing having an annular receiving port, a cylindrical valve 35 slidingly mounted in said casing and adjustably connected with the thermostatic couple to be moved positively and directly thereby, and means independent of said valve for supplying fuel to the fuel receiving port, said valve being provided with an annular port 40 cooperating with the port in the valve casing in receiving the fuel from the casing port and in controlling the flow of the fuel through the casing, and the valve being further provided with longitudinal ports establishing communication between the annular 45 port and the discharge side of the valve.

2. In a gas stove, the combination of a heating chamber, a main heating burner therefor, a pilot burner for igniting the main burner, a thermostatic couple located within 50 the heating chamber, a valve casing having a gas receiving chamber and a gas supply chamber, a valve connected to the thermostatic couple and controlling the flow of gas from the receiving chamber to the supply 55 chamber, a by-pass communication between said chambers, a pipe leading from the supply chamber to the main heating burner for supplying gas thereto, connections for delivering gas to the receiving chamber, and a

65 pipe leading from the receiving chamber to the pilot burner for supplying the same continuously with gas independently of the supply to the heating burner.

3. In a thermostatic fluid controlling device, the combination of a valve casing, a 70 thermostatic couple, a valve adjustably connected directly to said couple and controlling the flow of fluid through the casing, a dial head operatively connected with the valve and adapted to rotate the valve for adjusting 75 it relatively to the thermostatic couple, said dial head being provided with graduations, and a pointer fixed relatively to the dial head and in connection with which said graduations are adapted to be read, said pointer 80 being provided with graduations adapted to be read in connection with those on the dial head, and being adjustable relatively to the dial head in the direction of the spacing of the graduations.

4. In a thermostatic fuel controlling device for gas burners or the like, the combination of a thermostatic couple subject to heat generated by the burner, a valve casing having a fuel receiving chamber and a fuel supply chamber, and provided with a valve cylinder 90 formed with an elongated port in constant communication with the fuel receiving chamber, a piston valve adjustably connected directly to the thermostatic couple and arranged to slide in the valve cylinder, said piston valve being provided with an elongated port cooperating with the first mentioned port in controlling the flow of the fuel from the fuel receiving chamber to the fuel supply chamber, and being provided with axial ports 95 in constant communication with said elongated valve port and with the fuel supply chamber, and gas-tight means for adjusting the valve longitudinally with reference to the 100 thermostatic couple.

5. In a thermostatic fuel-controlling device, the combination of a valve casing, a thermostatic couple, a valve adjustably connected to said couple and movable by the latter to control the flow of fuel through the casing, and a tapered member rotatably mounted in a correspondingly formed bearing opening in the outer wall of the valve casing, said member being engaged with the valve for adjusting it, a spring for holding the tapered member gas-tight to its seat, and a dial head connected to the tapered member for rotating the same in adjusting the 110 valve.

In testimony whereof, I have affixed my signature hereto.

HENRY W. O'DOWD.
